CALCULATING MACHINE

Lee R. Brown, Whippany, N. J., assignor to Monroe Calculating Machine Company, Orange, N. J., a corporation of Delaware

Application May 16, 1935, Serial No. 21,712

2 Claims. (Cl. 235—138)

The invention has relation to calculating machines, and more particularly to tens carrying mechanism therefor. The invention consists in the novel construction and combination of parts as set forth in the appended claims.

In the accompanying drawing, illustrating the invention:

Fig. 1 is a vertical sectional view through the carry mechanism and associated parts, the members being shown in normal position of rest.

Fig. 2 is a side elevation of a series of carry dogs and associated parts.

Fig. 3 is a plan view of the same.

Fig. 4 is a detail view of a cross member, carry tooth and carry dog.

In this drawing the invention is illustrated as applied to a machine of the Monroe type, illustrated in United States Patent No. 1,474,230, granted to E. F. Britten, Jr. on November 13, 1923. In this machine the differentially set actuators and the tens carry elements are mounted upon separate shafts which shafts are rotated in one direction for performing positive or additive calculations and in the opposite direction for performing negative or subtractive calculations. The tens carry mechanism is of the preset type.

In the drawing, the numeral 1 designates a numeral wheel, of which a series is provided, mounted upon the shaft 2, and each having fast therewith a pinion 3, adapted to mesh with an intermediate gear 4, which gear is operated by the differentially set actuators and by the tens carry mechanism. Each wheel 3 is provided with a projection 5 lying in the plane of a tooth 6 of a settable carry member 7 pivoted at 8 upon a supporting shaft and provided with a U shaped spring 9 tending to hold the member 7 in either of two adjusted positions. A series of stationary collars 10 separate the intermediate gears 4, each collar being provided with a notch forming a seat for one of the springs 9, one branch of the spring engaging the bottom of the seat, and the other branch engaging a seat of the settable member 7, and acting to hold said member in adjusted position, in known manner. Upon displacement of the member 7 from the position illustrated in Fig. 1, by the action of projection 5, an oppositely beveled cam portion 11 of said member is brought into the path of rotation of a carry dog 17.

50 A series of discs 13 are splined upon a drive shaft 14, said discs being connected by cross members 15. The carry teeth 12 each form one part of a two-part member or dog, two spiral series of such dogs being mounted between the discs 13 for operation in forward or reverse rotation of

the shaft 14, in known manner. The teeth 12 are slidably mounted in bearings of the discs, and are normally held in retracted position by means of springs 16. Pivoted to each tooth 12 is a dog 17 held by the related spring 16 in engagement with a lug 18 of the carry tooth, each dog having a lug 19 engaging a spur 20 of the cross member 15. The cross member 15 is also provided with a spur 21 to which the spring 16 is attached.

A numeral wheel 1 having passed from 9 to 0 or from 0 to 9 registering position, pin 5 engages tooth 6 and adjusts the settable member 7 so that the cam portion 11 lies between the discs 13. Should a rotation of shaft 14, thereafter bring a dog 17 past the cam portion 11 the dog 17 will strike one of the bevel faces of said cam portion and the dog and tooth 12 will be slid as a unit, to bring the end of tooth 12 into position to engage between the teeth of the intermediate gear 4 related to the higher order numeral wheel 1, as illustrated by the position of the second carry dog in Fig. 2. Thus one step of additive or subtractive movement will be imparted to said higher order wheel. If, however, a dog 17 is located beneath the cam portion 11 at the time the settable member 7 is displaced by pin 5, dog 17, taking a bearing against the spur 20 of cross member 15, will push outwardly at its point of pivotal connection with tooth 12, projecting said tooth into position to engage the teeth of the higher order intermediate gear 4, as seen in the position of the right hand carry dog in Fig. 2.

The carrying movement being completed, settable member 7 will be restored to normal position, by engagement therewith of a pin 22 of the disc 13.

Since the teeth 12 will be properly positioned by the settable member 7, even after such teeth have come to position below the cam portion 11, these teeth may be spaced apart from each other by very narrow angular intervals, without interfering with the successive action of the parts when a higher order carry results from a lower order carry action. Therefore, since the peripheral extent of the series of carry teeth is reduced, the teeth may have a shorter radius about shaft 14, reducing the peripheral speed of rotation of the teeth and thereby reducing the speed of the entire carry action.

I claim:

50 1. In a tens carry mechanism for calculating machines, the combination with numeral wheels provided with projections, gears related to said wheels, and a settable cam faced member adapted to be displaced by a projection as the related

55

55

- wheel moves between 9 and 0 registering position; of a drive shaft, and a two-part dog mounted for rotation with said shaft and adapted to be cammed as a unit by the displaced settable member or alternatively to be extended by pressure of the settable member during displacement, to move a tooth portion of the dog into position to contact the gear related to the wheel of next higher order.
- 5 2. In a tens carry mechanism for calculating machines, the combination with numeral wheels provided with projections, gears related to said wheels, and a settable member adapted to be

displaced by a projection as the related wheel moves between 9 and 0 registering position; of a drive shaft, a spring retracted tooth mounted for rotation with said shaft and provided with a shoulder, and a dog pivotally mounted upon said tooth, yieldably engaging the shoulder thereof and adapted for engagement by the displaced settable member upon either of two right angularly disposed faces, to move the tooth into position to contact the gear related to the wheel 10 of next higher order.

LEE R. BROWN.
